UNITED STATES PATENT OFFICE.

WILMER G. BUCK, OF WARREN, OHIO.

PLOW.

1,095,308.

Specification of Letters Patent.

Patented May 5, 1914.

Application filed December 14, 1912. Serial No. 736,816.

To all whom it may concern:

Be it known that I, WILMER G. BUCK, a citizen of the United States, residing at Warren, in the county of Trumbull and State 5 of Ohio, have invented certain new and useful Improvements in Plows, of which the following is a specification.

The present invention relates more particularly to that class of plows adapted to 10 be driven by a gasoline or other suitable motor and commonly termed traction plows.

The objects of the present invention are 15 to provide means for raising and lowering the plow bodies into and out of plowing position in rotative order whereby all of the plows begin their plowing action at a certain point in the field and are all raised out of plowing position at a certain point in the field, thus making the commencement of all 20 furrows and the ends of all furrows in line.

The invention further consists in the features of construction and combination of parts hereinafter described and claimed.

In the drawings: Figure 1 is a bottom 25 view of a plow equipped with the mechanism of the present invention. Fig. 2 is a side elevation of said plow. Fig. 3 a sectional view of the transmission mechanism for driving the tractor wheel. Figs. 4, 5, 6, 30 and 7 are diagrammatic illustrations of the operation of the mechanism for raising and lowering the plow bodies. Fig. 8 a perspective showing the arrangement with respect to one another of the cams for raising and lowering the plow bodies, and Fig. 9 a sectional 35 view of the means for driving the shaft upon which the cams are mounted.

Referring to the drawings and particularly to Fig. 1 the machine or structure as 40 illustrated comprises a frame 15 which may be of any suitable size and style, and which in the form illustrated, comprises a front rail 16, side rails 17 and an obliquely extending rear rail 18. Mounted upon the 45 side rails 17 are suitable journals or bearings 19 which support a shaft 20 upon which is mounted the traction wheel 21. Said wheel in the construction shown is composed of four sections although this number may be 50 varied without departing from the scope of the present invention. Each section is a wheel by itself and is adapted under certain conditions to be revolved independently of the others. The outer sections 22 and 23 55 are joined respectively to the inner sections

24 and 25, and the wheels 22 and 24 may be said to constitute one set and the wheels 23 and 25 another set, said sets being arranged to lie one next to the other, and each of the sections is provided about its periphery with 60 suitable treads 26 to enable the wheels to more firmly grip ground in traveling. The sections 22 and 24 are joined together by means of a ratchet and pawl connection, thus when the section 22 is revolved in one 65 direction it will carry the wheel 24 therewith in the same direction, but when the direction of movement of the wheel or section 22 is reversed the pawl will slide over the teeth of the ratchet and no movement will 70 be imparted to the wheel 24 by the movement of the wheel 22. The wheels 23 and 25 are also joined together by a dog and ratchet connection, the wheels 22 and 24 may be said to constitute one set, and the wheels 75 23 and 25 may be said to constitute a second set. By this arrangement all of the sections 22, 23, 24, and 25 may be revolved in a common direction when desired and the movement of one of the outer of said section of one set may be reversed with respect to the movement of the other set for the purpose of turning the plow around, this feature will, however, be more clearly 80 pointed out hereinafter.

The traction wheel in the construction shown is driven by means of a suitable motor 29 mounted upon the frame of the machine.

In the construction shown in the drawings the drive from the motor is of the friction type, and a driven wheel 30 of the driving mechanism is connected to a shaft 31 which carries a gear 32 adapted to slide longitudinally thereof by actuating any 90 suitable form of lever mechanism. The driven wheel or disk 30 is slid in and out from the center of the driving disk to vary the speed of the driven shaft.

A fly-wheel 33 is positioned on the end of 100 the shaft 31 in order that auxiliary machines or devices of one kind or another may be driven by the motor when desired. The gear 32 is intended to mesh with either the gear 34, 35 or 36 of a differential gear mechanism 37, which gear mechanism drives and actuates the shafts 38 and 39. The shaft 38 has secured thereto a gear 40 which meshes with a gear 41 which is attached to the section 22 of the traction wheel, and the shaft 110

39 has secured thereto a gear 42 which meshes with a gear 43 that is attached to the section 23 of the traction wheel. The operation of the differential gear mechanism is well known and does not need to be described in detail at the present time. It is sufficient to say that when the gear 32 is in mesh with the gear 35 the shafts 38 and 39 and the gears 40 and 42 are revolved in the same direction and thus the sections 22, 23, 24, and 25 are rotated in the same direction. This will be the conditions when it is desired to propel the plow in a straight or relatively straight line.

15 If the gear 32 be shifted into mesh with the gear 34, the shaft 38 will, through the action of the differential remain stationary with respect to shaft 39, the gears 40 and 42 will thus be idle at this time and the sections 20 23 and 25 will continue in their forward direction of rotation while the section 22 will remain stationary. Under these conditions the plow will be turned about the section 24. If it is desired to turn in an opposite direction the gear 32 will be brought 25 into mesh with the gear 36, and under these conditions the sections 22 and 24 will be driven forwardly while the section 23 is held stationary. By this arrangement the turning of the plow when the end of the furrow 30 is reached or for any other reason is brought about by the simple action of shifting the gear 32, and the wheels which produce the turning are directly power driven. Hence 35 the necessary power to effect the turning is easily obtained.

By arranging the traction wheels at the forward portion of the frame, said wheels will to the extent indicated serve as steering 40 wheels. In order to produce slight turnings as for instance following a furrow which is more or less of an undulated or twisted formation I provide a steering wheel 44 best shown in Figs. 1 and 2. Said wheel is rotated by the manipulation of a hand wheel 45. The means for communicating movement from the hand wheel to the steering wheel may be in the nature of a rope or cable 45 or any other well known means practical for the purposes intended. The steering wheel as shown is located intermediate the traction 50 wheels and plows so that when turned it will swing the rear end of the frame carrying the plows about the traction wheels as a center thus disturbing the course of the traction wheels but slightly. When the gear 32 is out of mesh with all the gears 34, 35, 36 the shaft 31 alone is revolved, and under these conditions the machine will not be advanced, 55 but the power imparted to the fly-wheel 33 will be used for the purpose of actuating some auxiliary machine or device, as for instance a corn husker.

As will be seen more clearly from Figs. 1 60 and 2 of the drawings, the frame 15 has at-

tached thereto a series of plows. In the construction shown there are four plows, although this number may be varied as desired. The first plow as termed in order to expedite the description consists of a plow beam 46 to which is attached a plow body 47, the second plow consists of a beam 48 to which is attached a plow body 49, the third plow consists of a beam 50 to which is attached a plow body 51 and the fourth plow consists of a beam 52 to which is attached a plow body 53.

Each of the beams 46, 48, 50 and 52 terminates in an upturned end 54 as best shown in Figs. 2 and 4 to 7 inclusive. Each of the plow beams is supported by means of a depending lug 55 as shown in Fig. 2 to which it is pivotally attached by means of a pin 56 or other suitable means, and a guide for each of the plow means is provided, which consists of a slotted lug or plate 57 best shown in Fig. 2 in the slot of which travels a pin or protuberance attached to the plow beam. It is understood that there is a guide member and pivotal member for each of the plow beams.

By referring to the drawings and particularly to Figs. 1 and 2, it will be seen that the points of the plow bodies are so arranged with respect to one another as to extend in a diagonal line, so that under these conditions if all of the plows should be raised simultaneously when the end of the furrow is reached the furrows would be of unequal length and there would be considerable ground which would not be operated upon by the plow. One of the main features of the present invention is to provide a means for raising and lowering the plow bodies whereby they are raised and lowered in successive order; that is taking the present arrangement of plows, the plow member 53 would be first placed in the ground followed at successive intervals by the plow bodies 51, 49, and 47, and in raising the plows the plow body 53 will be first raised followed at successive intervals by the plow bodies 51, 49 and 47.

The method which I have illustrated as showing one means for carrying out this portion of the invention consists of a sleeve 59 surrounding the shaft 39 upon which are mounted a series of cams, 60, 61, 62 and 63, there being four cams in the construction shown because as illustrated the machine is equipped with four plows. It is understood, however, that the number of cams will vary in accordance with the number of plows with which the machine is equipped. The cam 60 is placed in operative position with respect to the upturned end of the beam 52. The cam 61 is in operative position with respect to the upturned end of the beam 50. The cam 62 is placed in operative position with respect to the 115 120 125 130

to the upturned end of the beam 48 and the cam 63 is placed in operative position to the upturned end of the beam 46.

By referring to Fig. 8 it will be seen that 5 these cams are so disposed about the sleeve 59 as to be out of alinement with one another so that they are brought into contact with the upturned ends of the beams with which they respectively engage in a rotative 10 or successive order. In the device illustrated the cam 60 will be the first to operate coming into engagement with the upturned end of the beam 52 and thus the plow 53 attached to this beam will be the first to be 15 raised from the ground. It might be noted that this is the one lying closest to the frame 15. Directly after the plow 53 has been raised the cam 61 will come into contact with the upturned end of the beam 50, and 20 the plow 51 will be raised next, and the lapse of time between the raising of the plow 53 and the plow 51 will be equal to the time necessary to have the machine move forward a distance equal to the distance 25 between the forward ends of the points of the plows 53 and 51, bringing the point of the plow body 51 up to the place where the point of the plow 53 left the ground. The cam 62 will next come into action and raise 30 the plow beam 48, and lastly the cam 63 will operate to raise the plow beam 46, thus each plow will be raised and discontinue its plowing action at the place where the plow 53 was raised whereby the furrows will all 35 be of uniform length all stopping at the same point. It will be understood that each of the cams is of sufficient length so that after the sleeve 59 has revolved far enough to bring all four cams into action the first 40 cam to be brought into action, namely the cam 60 will have been revolved until its entire surface has practically passed across the upturned end 54 of the beam 52, so that when all of the plows are raised and rotation 45 of the sleeve 59 is discontinued, the cams will then be in position so that upon further rotation of the shaft the cam 60 will pass off from the upturned end of the beam 52 allowing this beam and the plow 50 body 53 to drop, placing the plow body in position to have it again commence its plowing operation. The cams are so timed as to 55 action, that when the plow 51 shall have been brought up to the point where the plow 53 commenced its plowing operation, the cam 61 will release from the upturned end 54 of the plow beam 50 allowing the beam 50 and the plow body 51 to drop, whereby this plow body is placed in position to begin 60 its plowing operation. The cam 62 will next release itself from the upturned end of the beam 48 and lastly the cam 63 will release itself from the upturned end of the beam 46. By this arrangement the 65 plows are dropped into plowing position in

successive or rotative order whereby they begin their plowing action at the same point, thus making the furrows all commence at the same point.

It is desirable to rotate the shaft 59 with 70 an intermittent movement and to carry this out I employ a slotted disk 64, as shown in Fig. 2, and this disk is intended to be rotated by engagement of a pin 65, Figs. 1 and 9, which is carried by a channeled revolving disk 66. This disk 66 is revolved through the action of the gear 43 when a suitable clutch 67 is operated to connect the same, and this clutch may be operated by a suitable lever mechanism 68; thus by the 80 movement of this single lever mechanism the operator may raise and lower the plow body as desired.

The mechanism for actuating the sleeve 59 is so timed as to raise and lower the plow 85 bodies in accordance with the movement of the traction plow, thus insuring an evenness of furrow which could not be obtained, were all the plows raised and lowered as a unit at one time and at one operation, although the operator is not caused any further labor than would be necessary in raising and lowering plows all at a single operation.

It is understood that the precise details of 95 construction shown and described may be varied as desired provided that the invention is maintained within the scope of the language of the appended claims.

By removing the two intermediate sections of the traction wheel and using only the outer sections the sections will be arranged to straddle the rows of plants etc. in the field, and by employing cultivators or similar instruments instead of plows, the 105 device can be used as a motor driven cultivator.

I claim:

1. In a plow, the combination of a frame, a series of plow beams connected to said frame, a plow body joined to each beam, a shaft, means for rotating said shaft, a series of cams on said shaft, one for each plow beam, said cams being disposed about said shaft out of alinement with one another longitudinally of said shaft whereby they are successively brought into engagement with said beams and the plows raised and lowered in successive order, substantially as described.

2. In a plow, the combination of a frame, a traction member, a series of plow beams connected to said frame, a plow body joined to each beam, a shaft, means operatively connected for rotating said shaft by movement of said traction member, a series of cams on said shaft, one cam for each plow beam, said cams being radially disposed about said shaft and out of alinement with one another longitudinally of said shaft.

whereby they are successively brought into engagement with said beams and the plows raised and lowered in successive order, substantially as described.

5. 3. In a plow, the combination of a frame, a series of plow beams connected thereto, a plow body attached to each beam, a pivotal mounting for each plow beam located intermediate its ends and closer to the forward 10 than the rear end of the beam, a lifting member for each beam bearing directly against the forward end thereof and having no positive connection with the beam and means for operating said lifting members, 15 substantially as described.

4. In a plow, the combination of a frame, a series of plow beams connected to said frame, a pivotal mounting for each plow beam located intermediate its end and closer 20 to the forward than the rear end of the beam, a series of lifting members, one member for each beam, each of said members acting directly against the forward end of the beam with which it is associated, said lifting 25 members being disposed in different relative positions with respect to the beams whereby they are brought into active engagement with their respective beams in successive order and means for operating 30 said lifting members, substantially as described.

5. In a plow, the combination of a frame,

a series of plow beams connected to said member, a plow body connected to each beam, a pivotal mounting for each beam 35 located intermediate the ends thereof and closer to the forward than the rear end of the beam, a series of cams, one for each beam, each cam acting directly against the forward end of the beam with which it is 40 associated, said cams having their acting surfaces in different relative positions with respect to the beams whereby they are brought into acting engagement with the respective beams in successive order, and 45 means for operating said cams, substantially as described.

6. In a traction plow, the combination of a main supporting frame, traction wheels, a main driving shaft for the traction wheels, 50 means for driving said shaft, a sleeve loose on said shaft, a series of plow beams, a plow body attached to each beam, a pivotal mounting for each beam, a series of plow 55 lifting members on said sleeve, one for each beam, and means for rotating said sleeve with an intermittent movement to bring said lifting members into and out of lifting engagement with said beams, substantially as described.

WILMER G. BUCK.
